[57] CLAIM

The ornamental design for a continuous passive motion system drive cover, as shown and described.

DESCRIPTION

FIG. 1 is a perspective view of a continuous passive motion system drive cover showing our new design, the carriage being illustrated in broken lines and forming no part of the claimed design.

FIG. 2 is a top plan view of the continuous passive motion system drive cover;

FIG. 3 is a side elevational view as seen from the side shown in FIG. 1;

FIG. 4 is a side elevational view as seen from the side opposite that shown in FIG. 3;

FIG. 5 is a rear elevational view thereof; and

FIG. 6 is a front elevational view thereof.
